(57) **CLAIM**

The ornamental design for a table, as shown and described.

DESCRIPTION

FIG. 1 is a top perspective view of the table;
FIG. 2 is a top plan view of the table;
FIG. 3 is a bottom plan view of the table;
FIG. 4 is a back elevation view of the table;
FIG. 5 is a back perspective view of the table;
FIG. 6 is a front elevation view of the table;
FIG. 7 is a front perspective view of the table;
FIG. 8 is a left elevation view of the table;
FIG. 9 is a left perspective view of the table;
FIG. 10 is a right elevation view of the table; and,
FIG. 11 is a right perspective view of the table.

Broken lines depict table legs and a portion of the bottom of the table which form no part of the claimed design. In FIG. 3, the perimeter edge of the table, depicted by a solid line, is the only portion of the bottom of the table which forms part of the claimed design. All surface areas and legs of the table visible in FIG. 3 form no part of the claimed design.

1 Claim, 11 Drawing Sheets
